UNITED STATES PATENT OFFICE.

JESSE VAN DENBURGH, OF CHICAGO, ILLINOIS.

SCREW-CUTTING MACHINE.

SPECIFICATION forming part of Letters Patent No. 310,337, dated January 6, 1885.

Application filed June 2, 1884. (No model.)

To all whom it may concern:

Be it known that I, JESSE VAN DENBURGH, a citizen of the United States, residing at Chicago, in the county of Cook and State of Illinois, have invented certain new and useful Improvements in Screw-Cutting Machines, of which the following is a specification, reference being had therein to the accompanying drawings.

10 My invention relates to new and useful improvements in screw-cutting machines; and the novelty consists in the construction, arrangement, and adaptation of parts, as will be more fully hereinafter set forth, and specifically pointed out in the claims.

15 The essential objects and purpose of the invention are to produce a device which will cut the thread upon bolts, rods, and the like easily and readily, and allow the bolt or rod 20 to have its thread cut and the cutting-dies to be disengaged therefrom without running them back off the thread so cut.

25 The invention is designed as an improvement upon the device set forth in Patent No. 251,322, of 1881, in which power was applied to a hollow mandrel through a pulley which ran loose when the cutting-dies were not in operation. A clutch engaged a cam and sleeve with the hub of the pulley, and cam-slots in 30 the sleeve moved pins to cause the die-carriers to open and withdraw the dies from the blank being operated upon. In that patent the die-carriers, when withdrawing the dies from their service, turned on pivots, and had a swinging movement on said pivots as forced 35 by the cam-slots. This I find to be objectionable, and the present improvements are designed to provide such a construction that the carriers will be withdrawn in a direct line, 40 the vibration be greatly decreased, and the angle of the cam-slots be such that the required work may be done with much more ease. With this explanation it will only be necessary to describe briefly the parts of the 45 device which bear directly upon the improved construction and arrangement.

The invention is illustrated in the accompanying drawings, which form a part of this specification, and in which—

50 Figure 1 is a front end elevation; Fig. 2, a longitudinal side elevation, and Fig. 3 a similar view taken at right angles thereto.

Referring to the drawings, in which similar letters of reference indicate like parts in all the figures, A A designate the die-carriers, which operate in recesses C in the back piece, B, and they are provided each with laterally-projecting arms D D, which operate loosely in the cam-slots D' D', as shown, to give said carriers a direct motion when forced in either direction by the action of the cam-slots D' upon the arms D. The slots D' are formed in the cam-plates E, which are secured to the sleeve F, which sleeve has a longitudinal movement upon the shaft or mandrel, and may be impelled by any proper means—as, for instance, by means similar to those mentioned in the patent hereinbefore referred to. The die-carriers A are held in their position in the recesses C by means of the T-shaped pieces H, which pieces are firmly secured to the back pieces, B, by screws I, as shown in Figs. 2 and 3, and the position of the dies is adjusted by means of the screws G.

The operation of the device will be obvious. 75 The elements of novelty in this invention accrue, essentially, to the sliding carriers, with means for moving them in a direct line, and their relations with the T-pieces H, cam-plate E, having slots D', the dies, and the adjusting 80 means.

What I claim as new, and desire to secure by Letters Patent of the United States, is—

1. In combination with the longitudinally-moving sleeve of a screw-cutting machine, substantially as described, and with the cam-slots D', the die-carriers A, having arms D, adapted to carry the dies, and to be moved outward or inward in a direct line, as set forth. 85

2. The combination of the cam-plates E, having cam-slots D', with the die-carriers having arms D, the adjustable dies, as shown, the T-pieces H, and screws I and G, as and for the purpose set forth. 90

In testimony whereof I affix my signature in presence of two witnesses.

JESSE VAN DENBURGH.
